United States Patent Office.

WILLIAM MATHEWS, OF TROY TOWNSHIP, OHIO.

Letters Patent No. 77,746, dated May 12, 1868.

IMPROVEMENT IN PURIFYING SORGHUM-JUICE.

The Schedule referred to in these Letters Patent and making part of the same.

TO ALL WHOM IT MAY CONCERN:

Be it known that I, WILLIAM MATHEWS, of Troy township, in the county of Morrow, in the State of Ohio, have invented a new and improved Mode of Purifying Sorghum-Juice, Sorghum-Sirup, or any other kind of juice or sirup used in the making of molasses or sugar; and I do hereby declare that the following is a full and exact description thereof, reference being had to the accompanying drawings, and to the letters of reference marked thereon.

The nature of my invention consists in filtering the juice or sirup through a series of boxes, ranged in succession, as represented in the drawing, and filled with sand, charcoal, and gravel, as therein specified.

To enable others skilled in the art to make and use my invention, I will proceed to describe more fully its construction and operation, viz:

Figure 1 represents a perspective view, and

Figure 2 a sectional view.

b is a box, filled with coarse gravel; *c* is a box, filled with gravel and charcoal; *d* is a box, filled with gravel and sand; *a* is the funnel, by which the liquid is introduced; *e* is the orifice through which the liquid issues after passing through the filtering-ingredients.

In actual operation, two or more boxes of each kind of the filtering-ingredients specified are used, being arranged in succession, to suit the convenience of the operator.

What I claim as my invention, and desire to secure by Letters Patent, is—

The improved filterer herein described, composed of the vessels *b c d* or their equivalents, arranged and charged with filtering-materials, substantially as described.

WILLIAM MATHEWS.
